UNITED STATES PATENT OFFICE.

FRANCIS M. DEAN, OF ANACORTES, WASHINGTON.

MATRIX-RETAINER.

1,152,711.

Specification of Letters Patent. Patented Sept. 7, 1915.

Application filed January 19, 1915. Serial No. 3,104.

To all whom it may concern:

Be it known that I, FRANCIS M. DEAN, a citizen of the United States, residing at Anacortes, in the county of Skagit and State 5 of Washington, have invented certain new and useful Improvements in Matrix-Retainers, of which the following is a specification, reference being had to the accompanying drawings.

10 This invention relates to an improved matrix retainer, such as is commonly used by dentists for clamping or holding a tooth matrix, and the present invention has for its primary object to provide a very simple 15 and efficient device of this character which may be easily and quickly operated to securely clamp and hold the matrix.

It is a further object of the invention to provide a device of the above character, in 20 which the use of adjusting screws, nuts and the like, is entirely eliminated, and a device thus produced which will be extremely strong and durable in practical use and capable of manufacture at relatively small 25 cost.

With the above and other objects in view, my invention consists in the novel features 30 of construction, combination, and arrangement of parts to be hereinafter more fully described, claimed, and illustrated in the accompanying drawing, in which,

Figure 1 is a perspective view of my improved matrix retainer, showing the same in closed position; Fig. 2 is a side elevation, 35 the clamping jaws being open; and Fig. 3 is a longitudinal section of the device.

Referring in detail to the drawing, 5 designates spaced substantially triangular-shaped plates, which constitute the bearing 40 for the operating levers later referred to. A rod, indicated at 6, is disposed centrally between these two bearing plates and projects outwardly therefrom to a considerable distance beyond their wider ends. This rod is 45 rigidly held in place by means of the rivet 7 which connects the triangular-shaped bearing plates at their apexes.

8 designates the operating levers which are identical in form, and are pivotally 50 mounted between the corners of the bearing plates 5 upon the connecting rivets 9. Adjacent to these latter ends of the levers, the same are formed with the laterally projecting arms 10. The extremities of the longer 55 arms of the levers 8 are disposed at right angles to the arm and extended in relatively

opposite directions, as at 11, to provide suitable finger pieces, whereby said levers may be conveniently actuated. The gripping or retaining jaws 12 are longitudinally curved and arranged in opposed relation upon opposite sides of the rod 6. At the inner ends of said jaws, the same are reversely curved and formed with obliquely disposed extensions 13, the extremities of which are bifurcated and pivotally connected as at 14, to the shorter arms 10 of the operating levers. The upper free ends of the retaining jaws 12 are preferably formed with the terminal spurs or gripping points 15. The reversely curved inner end portions of these jaws are connected upon opposite sides by the links 16, said links being disposed upon opposite sides of the central rod 6.

In the operation of my improved matrix retainer as above described, assuming that the jaws have been opened to the position shown in Fig. 2, the matrix is arranged between the same, and the operator swings the levers 8 downwardly and inwardly toward each other. The arms 10 of said levers are thus thrown outwardly and the opposed jaws 12 moved inwardly toward each other until the spurs 15 securely grip the matrix and retain the same in position between the jaws. The central rod 6 forms a guide for the jaws in their opening and closing movements. When the links 16 are disposed below the central portion of this rod, the pivots connecting said links with the jaws are 85 so located with respect to the pivoted ends of the jaw extensions 13, that said jaws cannot spread or separate. Such separation can only be effected by movement of the levers 8 outwardly away from each other. In this manner, it will be seen that I have produced a very simple and effective matrix retainer, 90 which may be easily and quickly operated to securely grip and retain the matrix. I have entirely dispensed with the use of adjusting 100 screws, nuts and like elements, which are commonly employed in devices of this character, and have, therefore, not only greatly simplified its construction, but also produced a matrix retainer which is of greater 105 durability.

While I have shown, in the accompanying drawing, and above described the preferred form, construction, and arrangement of the several elements employed, it is to be understood that the structural features of the device may be variously modified in such re- 110

spects and the device also made in a number of different sizes, without departing from the essential features or sacrificing any of the advantages of the invention as claimed.

5 Having thus fully described my invention, what I desire to claim and secure by Letters Patent is:—

1. A device of the character described including opposed retaining jaws having 10 obliquely disposed extensions formed on one end, a bearing, opposed levers pivotally mounted on said bearing and provided with laterally extending arms connected to the 15 extensions of the respective retaining jaws, and link connections between the inner ends of said jaws at their juncture with said extensions.

2. A device of the character described including opposed retaining jaws having 20 obliquely disposed extensions at their inner ends, a bearing, opposed operating levers pivotally mounted on said bearing, each of said levers being provided with a laterally disposed arm on its pivoted end, the arms 25 of said levers being connected to the extensions of the respective jaws, a longitudinally extending rod fixed at one end to said bearing, and link connections between the jaws 30 at their inner ends disposed upon opposite sides of said rod.

3. A dental matrix retainer including a bearing, opposed retaining jaws, means independent of the bearing connecting said jaws for relative movement, and a pair of

levers mounted upon said bearing and connected to the respective jaws to move the jaws in unison with respect to said bearing, said levers in one position locking the jaws in closed engagement with the matrix. 35

4. A dental matrix retainer including a 40 bearing, opposed retaining jaws, guide means for said jaws fixed to the bearing, and levers pivotally mounted upon the bearing and connected to the inner ends of the respective jaws to move the jaws in unison 45 longitudinally with respect to said bearing and in one position lock the jaws closed upon the matrix.

5. A dental matrix retainer including a 50 body, opposed retaining jaws, means independent of the body connecting said jaws to each other, and levers pivotally mounted upon said body and having pivot connections with the respective jaws at their inner ends, said levers moving the jaws in unison longitudinally with respect to the body and in one position disposing the pivot connections 55 between the jaws and the levers with respect to the pivot connections between the levers and the body whereby the jaws are locked 60 in their closed position upon the matrix.

In testimony whereof I hereunto affix my signature in the presence of two witnesses.

FRANCIS M. DEAN.
